UNITED STATES PATENT OFFICE.

JOSEPH LAVOIE, OF MANCHESTER, NEW HAMPSHIRE, ASSIGNOR TO DRAPER CORPORATION, OF HOPEDALE, MASSACHUSETTS, A CORPORATION OF MAINE.

HARNESS STOP MOTION.

Application filed March 10, 1922. Serial No. 542,600.

To all whom it may concern:

Be it known that I, JOSEPH LAVOIE, a subject of King George V of Great Britain, residing at Manchester, in the county of 5 Hillsboro and State of New Hampshire, have invented an Improvement in Harness Stop Motions, of which the following description, in connection with the accompanying drawings, is a specification, like characters on the drawings representing like parts.

This invention relates to looms, and more particularly to the harness stop mechanism by which the loom is brought to rest when 15 a harness frame connection becomes broken or too slack for weaving purposes.

During the operation of weaving, the harness frames which control the warp threads are raised and lowered in a predetermined sequence to form the successive sheds through which the shuttle is passed to lay the filling or weft thread. Should one or more of the connections between the harness frames and the associated devices 25 become broken, it is evident the released harness frame will no longer respond to the predetermined sequence of shed formation and improper weaving will result.

The object of the present invention is to 30 provide the harness stop mechanism which has become effective to stop the loom when an upper or a lower connection to any harness becomes broken or too slack. The present invention therefore, comprises a stopping mechanism to bring the loom to 35 rest, and two trains of mechanism acting therethrough, to cause the stop mechanism to operate and stop the loom when a heddle frame connection, either above or below, becomes broken or unduly slack. Each of the 40 trains of mechanism act through the same stopping mechanism, and each of said trains of mechanism contains novel features.

In the drawings:—

Figure 1 is a perspective view of portions of the loom with parts broken away and showing more particularly the stopping mechanism and the two trains of mechanism acting therethrough to stop the loom;

Fig. 2 is a front view of sufficient of the loom containing the present invention to make clear the relation and association of parts; and

Fig. 3 is a fore-and-aft section of the loom 55 at the lower part thereof, showing more par-

ticularly the means for depressing or pulling down the harness frames in the formation of the sheds.

The general construction of the loom, its operating mechanism for weaving cloth, and the various accessories utilized in this connection are or may be of old and usual construction and need not therefore be herein shown and described.

The loom frame 1 is of usual construction, and is provided with the overhead supporting member or arch 2. Any number of heddle frames may be employed in accordance with the design of the cloth to be woven, and in the present instance four of such frames are shown. Each harness frame is supported by tensioned suspending connections, and is lowered in accordance with the design of the cloth to be woven by suitable means acting upon the lower connections with the harness frames for lowering them in predetermined order in forming the sheds.

Each harness frame 3 carries a series of heddles 4 provided with the usual eyes through which the warp threads are passed singly in a desired order. Each harness frame has the tensioned suspending connections 5 which pass upwardly about the guide rolls 6 mounted for free rotative movement upon their respective brackets 7 and 8 carried by the loom arch, and each of the connections 5 has associated therewith a spring 9, two of which are shown in Fig. 2, it being understood that each harness frame has a spring associated with its overhead suspending means or straps.

In the present instance of the invention, the bracket 6 is turned laterally at its upper portion 9 and carries the guide sheaves 10 about which pass portions 11 of the overhead connection with the harness frames. Each connection or strap 11 has attached thereto one end of a spring 9, the other end of which is provided with a slotted guide 12, into the slot of which extends a guide lug 13 projecting from the upward extension of the bracket 7, the construction being such that the tendency of the springs 9 is to lift or raise the associated harness frame.

Secured to and extending downwardly from each of the harness frames are the lower connections 14, Fig. 2, which in the present instance are shown as straps, the lower ends of which carry the usual eyes 15 for engagement with the toothed end por-

tion 16 of the shedding levers 17, one of such levers being provided for each of the connections 14 of each harness frame.

As shown in Fig. 3, the levers 17 are pivotally mounted on the loom frame or a suitable bracket secured thereto at 18, and each carries a roll 19 to be engaged by the shedding mechanism which, in the present instance, is in the form of cams 20 secured to the cam shaft 21 carried by the loom frame as usual. From the construction thus far described, it will be apparent that the springs 9 of the overhead connections with the harness frames are under tension which tends to lift or raise the harness frames and hold the rollers 19 of the shedding levers against their respective cams, so that during the operation of the loom, the harness frames are lowered against the tension of the springs 9 in the formation of the shed.

Mounted on the loom frame or as shown, upon the arch 2 at 22, are a series of actuators 23, one for each of the overhead connections, and each actuator 23 is joined to its associated overhead connection by a link, cord, or other suitable means 24. Each of the actuators 23, of which there are four in the present instance, is normally under the influence of a light spring 25, one end of which is connected to one of the actuators and the other to a fixed arm 26, as indicated in Fig. 1; and since the springs 25 are weaker than the tensioned suspending springs 9 of the overhead connections with the harness frames, it follows that the guides 12 will normally be held to the right, Fig. 2, with the guide lugs 13 engaged with the left end of the slot, which thus constitutes a stop or holding means.

Pivots supported adjacent the actuators 23 is a single indicating member 27, Fig. 1, the upper end portion of which is carried laterally at 28, and is normally held against the actuators 23 by a spring 29, one end of which is connected at 30 to a holding finger or lug 31, and the other end of which is connected at 32 to the laterally-extending arm 33 of the indicating member, so that under normal conditions the spring 29 holds the indicating member 27 in its normal position resting against the outer edge portions of the actuators 23, and the relation of the springs 25 and 29 is such that the parts will assume and remain in the position indicated in Figs. 1 and 2 under normal weaving conditions, or if desired, a stop pin 34 may be provided for limiting the action of the spring 29, Figs. 1 and 2.

The mechanism thus far described constitutes one train of mechanism for causing the stopping mechanism to operate to stop the loom when one or more of the overhead connections with the harness frames become broken or too slack. The stopping mechanism may be variously contrived, and

as shown in the present instance of the invention comprises a downwardly-extending link 35 pivotally connected to the arm 33 of the indicator and at its lower end joined to a pivoted dog 36 pivotally supported at 37 on the swinging link 38 which is itself pivotally mounted at 39 to the loom frame. The dog 36 has a fan-tail end 40 which is normally below the path of movement of a bunter 41 adjustably mounted on the lay 42. In the present instance the bunter 41 is formed as a lug adjustably secured to the lay by a bolt 43 which passes through an opening 44 in the bracket carried by the lay.

The swinging link 38 is connected to the shipper mechanism so that should the dog 36 be held rearwardly or to the left, Fig. 1, the shipper mechanism would be actuated to stop the loom. In the present instance the swinging link 38 carries the yoke portion 45 to which is pivotally connected the transmitter 46. The front end portion of the transmitter 46 has a slotted link 47, through the slot 48 of which extends a pin 49 secured to the shipper lever 50. The shipper lever 50 is of the usual construction, and when moved to the left, Fig. 1, causes the loom to stop through well-known means which is not necessary to be described herein, because they are well understood, and the details thereof form no essential part of the present invention. The slot 48 is provided in the link 47 to enable the shipper lever 50 to be moved to stopping position by hand or otherwise than by one of the trains of mechanism connected to or operated through the harness frames.

From the construction thus far described it will be apparent that should one of the overhead connections with any harness frame break, the tensioned spring 9 associated with that frame will be released, and, through its connection 24 with one of the actuators, the guide 12 will move to the left the length of the slot therein under the impulse of the spring 25 which controls the associated actuator 23. Movement to the left of the actuator 23, however, will at once cause the indicator 27 to move counterclockwise, viewing Figs. 1 and 2, thereby turning the dog 36 to present its fantail end portion 40 in the path of the bunter 41, which on rearward movement of the lay, will effect loom stoppage through the shipper.

It frequently happens that one of the lower or under connections with a heddle frame becomes broken or detached from its actuator or lever 17, and the present invention provides that in such case, also, the stopping mechanism shall be rendered effective to cause loom stoppage.

In the present instance the invention provides the harness feeler mechanism, and as shown by Figs. 1 and 2, such feeler mechanism includes two feelers, one located over

the heddle frames at each end thereof, and between the harness feelers and the stopping mechanism is a train of mechanism to cause the stopping mechanism to stop the loom when one of the under connections to a heddle frame becomes broken or too slack and the released heddle frame rises under the impulse of the tensioned suspending connection.

- 10 Each feeler as shown, comprises a hanger 51, Fig. 1, the lower portion 52 of which is extended fore-and-aft of the loom or substantially at right angles to the plane of movement of the harness frames, and directly above the plurality of harness frames. The upper end portion of the hanger 51 of each harness feeler is adjustably connected at 53 to one of the arms or levers 54, 55, each of which is connected through the indicator to the stopping mechanism for effecting loom stoppage when either of the harness feelers is raised by one of the harness frames, the under connection of which has become broken or too slack.
- 25 The arm 54 is preferably constituted as a lever pivoted at 56 to a support on the loom arch and has a hooked end portion 57 which overhangs and rests upon the arm 33 of the indicator. The weight of the overhanging arm 57 is sufficient ordinarily to hold the parts in the position indicated. The arm 55 is formed as a bell crank pivotally supported at 58 to a bracket 59 secured to the loom arch 2, and the upwardly-extending portion 59' is connected at 60 to a link 61 joined at 62 to the side of the indicator 27, Fig. 1. From the construction described, it will be apparent that should either one of the harness feelers be raised due to unusual upward movement of any one of the harness frames, such as would occur by the breakage of one of the lower or under connections, the associated arm 54 or 55 will be turned upon its pivotal support and through the connections with the indicator cause movement thereof to position the dog 36 for engagement by its fan-tail end 40 with the bunter 41 of the lay as the latter goes back, and thereby act through the stopping mechanism 50 to stop the loom.

It may happen that the upward movement of one of the harness frames is sufficiently impulsive and forceful that it is liable to impart to the indicator 27 undue movement so that the present invention contemplates the use of a stop 63, Fig. 1, against which the arm 33 of the indicator may strike to be limited in its movement under the actuation of one of the harness feelers. Thus the stop 63 acts as a determinator for positioning the fan-tail end of the dog 40 in the path of movement of the bunter 41 when either train of mechanism actuated by the breaking of an upper or lower harness connection is operated.

In case one of the upper harness connections is broken, the tensioning means or spring 9 associated therewith will be released and through the actuator and determinator, act as a train of mechanism upon the loom 70 stopping mechanism to bring the loom to rest. Likewise, should one of the lower connections to any harness frame become broken or too slack, the released harness frame or one end of it will at once respond to the lifting 75 tension of the suspending connection and rise into engagement with one of the harness feelers and lift it so that it will act through its train of mechanism to cause the stopping mechanism to effect loom stoppage. 80

What is claimed is:—

1. In a loom, the combination of a plurality of harness frames each having spring tensioned suspending connections normally tending to raise the harness frame, lower 85 connections with each harness frame for lowering the harness frames in forming the shed, loom stopping mechanism, and two devices cooperating with each harness frame, one for causing the stopping mechanism to stop the loom when the tension of the suspending connection with a harness frame is released by breakage or slackness of one of said suspending connections, and the other for causing the stop mechanism to stop the 95 loom when one of the lower connections breaks or becomes too slack and the harness frame rises under the action of the tensioned suspending means.

2. In a loom, the combination of a plural- 100 ity of harness frames each having spring tensioned suspending connections normally tending to raise the harness frame, lower connections with each harness frame for lowering the harness frames in forming the 105 shed, loom stopping mechanism, and two devices associated with a harness frame and connected to the stopping mechanisms, one for stopping the loom when a suspending connection breaks or becomes too slack and 110 the other for stopping the loom when one of the lower connections breaks or becomes too slack.

3. In a loom, the combination of a plural- 115 ity of harness frames each having tensioned suspending connections tending to raise the harness frame, lower connections therewith for lowering the harness frames in forming the shed, and two trains of mechanism each cooperating with a harness frame, one ren- 120 dered operative to stop the loom when one of the suspending connections breaks or becomes too slack and the connected harness frame drops and the other rendered operative to stop the loom when a lower connection 125 breaks or becomes too slack and the harness rises.

4. In a loom, the combination of a plural- 130 ity of harness frames each having tensioned suspending connections tending to raise it,

lower connections and means acting thereon for lowering the harness frames, loom stopping means, and two trains of mechanism cooperating with each one of the harness frames, one of which mechanisms is made effective to stop the loom, when one of the suspending connections breaks, and the other of which is made effective to stop the loom when one of the lower connections breaks and either end of the released harness frame is raised.

5. In a loom, the combination of two or more harness frames each having suspending straps normally under tension tending 15 to lift the connected harness frame, lower straps connected to each harness frame, means acting through the lower straps for lowering the harness frames in forming the shed, loom stopping mechanism, and two 20 devices cooperating with each harness frame to cause loom stoppage when there is a break in the heddle frame strap either above or below the harness.

6. In a loom, the combination of a plurality of harness frames each having suspending means normally under tension tending 25 to lift the connected harness frame, means for lowering the harness frames in opposition to the tensioned suspending 30 means in forming the shed, loom stopping mechanism, and two devices associated with each of the harness frames and connected to the stopping mechanism to stop the loom either when a harness frame drops due to 35 breakage or slackness of its suspending means, and another means for causing the stopping mechanism to stop the loom when a harness lowering means breaks or becomes too slack or rises due to a defect in 40 the harness lowering means.

7. In a loom, the combination of a plurality of harness frames each having separately tensioned suspending connections tending to raise it, lower connections with each harness, means acting on the lower connections 45 for lowering the harness frames in forming the shed, loom stopping mechanism, and a device extending above the harness frames 50 for causing the stopping mechanism to stop the loom when one of the lower connections breaks or becomes too slack and one of the harness frames is raised.

8. In a loom, the combination of a plurality of harness frames each having separately 55 tensioned suspending connections tending to raise it, lower connections with each harness, means acting on the lower connections for lowering the harness frames in forming the shed, loom stopping mechanism, a harness 60 feeler located above the harness and moved thereby when one of the lower con-

nections breaks or becomes too slack and the released harness frame rises.

9. In a loom, the combination of a plurality of harness frames each having tensioned suspending connections tending to raise it, lower connections, means acting on the lower connections for lowering the harness frames in forming the shed, a harness feeler which extends over the plurality of harness frames 70 at each end thereof that either end of any harness frame may engage and move one of the feelers when either end of a harness frame is raised due to breakage of a lower connection, and stopping mechanism made 75 effective to stop the loom when either harness feeler is raised.

10. In a loom, the combination of a plurality of harness frames each having tensioned suspending connections tending to raise it, lower connections, means acting on the lower connections for lowering the harness frames in forming the shed, a harness feeler supported over the tops of the series of harnesses, a loom stopping mechanism, and 85 connections between the loom stopping mechanism and the two harness feelers to cause the stopping mechanism to stop the loom when a harness feeler is moved by a harness whose lower connection has become 90 broken or too slack.

11. In a loom, the combination of a plurality of harness frames, each having an overhead tensioned suspending connection, loom stopping mechanism, separate spring actuated means connected to each of the tensioned suspending means and released upon breakage or undue slackness of the suspending means for movement under its spring actuation, a single member common to all 100 of said separate spring actuated means and movable by any one of them when the tensioned suspending connection breaks or becomes too slack to cause the stopping mechanism to stop the loom.

12. In a loom, the combination of a plurality of harness frames, each having an overhead tensioned suspending connection, loom stopping mechanism, separate spring actuated means connected to each of the tensioned suspending means and released upon breakage or undue slackness of the suspending means for movement under its spring actuation, a single spring-held member common to all of said separate spring-actuated means and movable by any one of them when the tensioned suspending connection breaks or becomes too slack to cause the stopping mechanism to stop the loom.

In testimony whereof, I have signed my 120 name to this specification.

JOSEPH LAVOIE.
